RETRACTABLE WALKING BEAM

Leslie A. Rawson, Los Angeles, Calif., assignor
to Emesco Derrick & Equipment Company, Los
Angeles, Calif., a corporation of California

Application January 15, 1934, Serial No. 706,685

13 Claims. (Cl. 74—41)

My invention is a walking beam construction for use in connection with a vertically reciprocating pump, such as is used in the oil-pumping industry, the construction being such that the walking beam is capable of being quickly and conveniently moved from an operating position into a retracted position.

In order that the features of construction of my invention may be better appreciated, I shall briefly refer to the oil-pumping industry for the reason that my invention has a marked utility in this connection. I do not mean to be understood, however, as limiting my invention to this capacity as various use thereof in several different industries might be made.

It is present practice to pump oil from a well by means of a pump situated in a well below the oil level. This pump includes a reciprocating plunger which is operated by means of a string of sucker rods connected thereto and extending upwardly to the surface of the ground. Mounted in the derrick of the well as a part of the surface apparatus is a reciprocatory walking beam which is journaled on a Samson post. One end of the walking beam is positioned directly above the well and the upper end of the string of sucker rods is attached thereto. Upon oscillation of the walking beam the string of sucker rods is alternately raised and lowered, thus reciprocating the pump plunger and pumping oil to the surface of the ground. The end of the walking beam remote from the well is connected by means of a pitman to what is ordinarily called a walking beam crank. This walking beam crank is mounted on the shaft of a band wheel, which upon rotation rotates the crank, causing the walking beam to be oscillated by the pitman.

It is necessary at certain times to remove the sucker rods, the pump or the tubing from the well, and in order to conveniently do this it is necessary that the upper end of the well be accessible and that portion of the derrick directly above the well be clear. It is ordinary practice to tilt the walking beam in its bearing on the Samson post so that the inner end thereof will be raised in an arc as far as possible in order to enable the use of hoisting apparatus in raising the sucker rods or tubing from the well. It is often necessary to disconnect the pitman from the walking beam in order that the end of the beam may be swung upwardly a sufficient distance to clear the well. This, however, is a rather difficult mode of procedure inasmuch as the pitman is usually provided with a counterweight weighing several hundreds of pounds, which, of course, requires

the use of hoisting apparatus to disconnect and lower the pitman to the derrick floor.

It is the primary object of my invention to provide a combination in which the walking beam is easily and quickly moved from an operating position into a retracted position without the necessity of disconnecting the walking beam from the pitman or any other apparatus than the sucker rods in the well.

My invention is designed primarily so that the movement of the walking beam between an operating position and a retracted position may be accomplished by one workman with a minimum of manual labor, and in a relatively short period of time.

It is another object of my invention to provide a combination of the character described in which the Samson post directly supports the weight of the walking beam in both an operating position and a retracted position.

It is another object of my invention to provide a retractable walking beam construction which includes means for adjusting the operating position of the walking beam with respect to the well and for moving the walking beam from the operating position into a retracted position.

It is another object of the invention to provide a combination as described in the above paragraph in which the Samson post is provided with a table upon which the walking beam is supported by a suitable bearing block which is slidable thereon so that the walking beam may be slid laterally away from the well, and in which is provided means for easily and quickly accomplishing this sliding movement of the walking beam.

It is another object of my invention to provide a combination of the character described in the above paragraph which is very simple and rugged in construction, which can be made cheaply and at the same time provide an efficient manner of retracting the walking beam away from the well quickly and easily, this being accomplished by one man.

These and other objects will be apparent from a perusal of the following part of the specification and the appended claims, together with the accompanying drawings.

In the drawings,

Fig. 1 is a utility view showing the general arrangement of the parts included in an oil well pumping apparatus and showing the device of my invention in connection with the walking beam of the apparatus.

Fig. 2 is a side elevational view partly in sec-

tion of that portion of the oil well pumping apparatus included in the combination which is my invention.

Fig. 3 is a plan view of the walking beam supporting table and the bearing block for journaling the walking beam.

Fig. 4 is a vertical sectional view taken as indicated by the line 4—4 of Fig. 2.

Fig. 5 is a vertical sectional view taken as indicated by the line 5—5 of Fig. 2.

Fig. 6 is a view comparable to Fig. 2 but showing an alternative form of the device.

Fig. 7 is a sectional plan view of the supporting table and the alternative form of bearing block, this view being taken as indicated by the line 7—7 of Fig. 6.

Fig. 8 is a vertical section taken as indicated by the line 8—8 of Fig. 7.

Referring to the drawings, and to Fig. 1 in particular, I show an oil derrick 11 which is built on the surface of the ground over a well 12. In the lower part of the well is a pump 14 having a plunger which is connected to a string of sucker rods 15. Surrounding the pump 14 is an oil tubing 16 by means of which the oil is conveyed to the surface of the ground. The string of sucker rods extends upwardly through the tubing 16 to a point above the surface of the ground. Situated in the derrick 11 adjacent the well 12 is a pumping apparatus generally designated by the numeral 20 which includes a Samson post 21 adapted to journal a walking beam 22. One end 23 of the walking beam 22 extends directly over the well 12 and is adapted for connection to the string of sucker rods 15. The other end 24 of the walking beam 22 extends outwardly from the derrick 11 and is pivotally connected to the upper end of a pitman 25, the lower end of which is in turn pivotally joined to a walking beam 26 mounted on the shaft 27 of a band wheel 28. The pitman 25 ordinarily includes a counterweight, indicated at 29, adapted to counterbalance the weight of the oil in the oil tubing 16.

When the band wheel 28 is rotated, the crank 26 is caused to rotate therewith which serves to oscillate the walking beam 22 through the medium of the pitman 25, thus reciprocating the pump plunger 14 to pump oil upwardly through the oil tubing 16.

Coming now to the more pertinent details of my invention I show one form thereof as providing a laterally extending walking beam supporting table on the upper end of the Samson post 21, which table is generally designated by the numeral 30. As best shown in Figs. 2 to 5 inclusive, the table 30 includes a pair of ways 31 and 32, which are conveniently formed by providing a pair of angle irons bolted to a pair of gusset plates 33 and 34, which are in turn bolted, or otherwise secured, to the upper end of the Samson post 21 in such a manner that the legs 35 of each of the angular ways 31 and 32 extend toward each other in relatively spaced relationship and in the same horizontal plane, as best shown in Figs. 4 and 5.

Referring to Figs. 2 and 3, the adjacent ends of the ways 31 and 32 on one end of the table 30, such as the leftward end 36 thereof, are connected together by means of an end plate 37 bolted or otherwise secured to the ways 31 and 32 to form a rigid construction. Formed in the center of the end plate 37 on a median line between the inner edges 39 and 40 of the legs 35, is a bearing 41 providing a bore 42.

The ends of the ways 31 and 32 at the other

end 43 of the table are connected together by a cross plate 45, suitably connected thereto to form a rigid construction, the upper surface of the plate 45 providing a recess which cooperates with a recessed cap 44 bolted to the plate 45, as shown, to form a bore 46 which is axially aligned with the bore 42.

Journalized in the bores 42 and 46 is an elongated lead screw 50 which is provided with threads 51 extending substantially the entire distance between the end plate 37 and the cross plate 45, as shown.

The rightward end 55 of the lead screw 50 is extended through the bore 46, as shown, and is provided with a pulley 56 adapted to serve as a convenient manner of manually rotating the lead screw 50 by means of a chain or cable 57.

The ways 31 and 32 of the table 30 are adapted to support the journaling means of the walking beam in such a manner that the journaling means and the walking beam may be moved relative to the Samson post 21 and the well 12 from an operating position into a retracted position, in which retracted position the end 23 of the walking beam is withdrawn from over the well. One form of mechanism for conveniently accomplishing this purpose includes a bearing block 60 which I have shown as comprising a casting providing downwardly facing skid surfaces 61 and 62 adapted to slidably rest upon the upper surfaces 63 and 64 of the ways 31 and 32, as shown best in Figs. 4 and 5. Formed at the outer edges of the skid surfaces 61 and 62 at right angles thereto are downwardly extending flanges 65 and 66 providing inwardly facing guide surfaces 67 and 68 adapted to slidably engage the outer vertical faces 69 and 70 of the ways 31 and 32, as shown, serving to guide the bearing block axially on the table 30 and parallel to the lead screw when the bearing block is slid longitudinally on the table 30. Any desired form of journaling means for providing a fulcrum for the walking beam may be used, such as a pair of cooperating members 75 providing a journal 76, the lower member 75 being securely bolted to the top of the bearing block 60 as shown in Figs. 1, 4, and 5.

Provided in the center of the bearing block is a squared opening 80 extending vertically through the body of the bearing block 60 as shown in Figs. 1 and 4, this opening being adapted to non-rotatably receive a square nut 81 which threadedly engages the lead screw 50. It will be clearly understood that when the lead screw 50 is rotated by means of the pulley 56, the nut 81 being non-rotatable relative to the bearing block 60 will travel longitudinally on the lead screw, serving to slide the bearing block longitudinally on the table 30.

Means for preventing torsional or vertical movement of the bearing block relative to the Samson post is provided in my invention. A convenient form adapted for this purpose is shown in Figs. 4 and 5. Formed integrally with the bearing block 60 on each side of the opening 80 below the plane of the legs 35 of the ways 31 and 32 is a longitudinally extending wall 85, these walls being connected together at their adjacent ends by integral webs 86. The longitudinally extending walls 85 cooperate with the bottom face of the bearing block 60 to form longitudinally extending outwardly facing channels 87 and 88, which are adapted to slidably receive the inner ends 39 and 40 of the legs 35 respectively.

In the preferred form of the invention the bearing block 60 is provided with a longitudinal

downwardly facing semi-circular groove 89 providing clearance for the lead screw. As shown in the drawings, there may be provided at points closely adjacent the opening 80 a pair of integral loops or strap members 90 and 91 which surround the lower half of the lead screw and form longitudinal bores 93 serving to provide additional aligning means between the screw 50 and the bearing block 60. This construction, however, is of course immaterial, the use thereof depending upon the plane at which the bottom surface of the bearing block 60 is formed relative to the axis of the lead screw 50 and the skid surfaces 61 and 62.

It is preferable in the preferred form of my invention to provide means for securing the bearing block in an operating position which is the position in which the end of the walking beam is directly over the well. It is desirable that lateral adjustment means be provided so that the correct operating position of the walking beam with respect to the well may be easily accomplished in the event that the Sampson post is not exactly positioned with respect to the well when the derrick is assembled. This purpose may be very simply accomplished by providing staggered rows of holes 95 and 96 in each of the ways 31 and 32 which are respectively aligned with holes 97 and 98 provided in the bearing block 60. In the operation of adjusting the walking beam in its operating position, certain of the holes in the bearing block 60, such as the holes 98, are respectively aligned with holes in the ways 31 and 32, such as the holes 96, or the holes 97 of the bearing block may be respectively aligned with holes 95 in the ways 31 and 32. When the proper operating position of the walking beam with respect to the well has been determined, bolts 99 are extended through the aligned holes in the block 60 and the ways 31 and 32, as shown in Figs. 3, 4, and 5, serving to rigidly secure the bearing block, and thus the walking beam against longitudinal movement on the table 30. When the correct operating position of the walking beam has once been determined upon installation in the derrick, the respective holes in the block 60 and the ways 31 and 32 may be marked, so that when the walking beam is retracted and then returned to operating position, the correct operating position will be known to the workman without additional measurements.

When it becomes necessary during the operation of pumping oil from the well 12 to remove the pump or to pull the tubing, it requires the labor of only one man to disconnect the sucker rods from the walking beam 22, remove the bolts 95, and by means of the pulley and chain 56 and 57 rotate the screw 50 to slide the bearing block 60 and the walking beam 22 laterally, in the direction of the arrow A of Figs. 1 and 2, into the retracted position shown in dotted lines "B" in these figures.

When the walking beam is fully retracted, as just described, the band wheel 28 is rotated until the crank 26 is in its lowermost position, shown by the dotted lines "C" of Fig. 1, which pulls the end 24 of the walking beam downwardly, and raises the end 23 thereof into its uppermost position. In this manner by moving the entire walking beam laterally away from the well, then by raising the inner end of the walking beam I am enabled to retract the inner end 23 of the walking beam so that the space 75 in the derrick above the well is entirely clear

for the use of the hoisting machinery required to lift the sucker rods therefrom.

I will now describe the alternative form of the invention disclosed in Figs. 6, 7, and 8. The differences of this form from the first described form reside solely in the construction of the slidable bearing block. In this form I provide a one-piece casting 100 having a substantially flat bottom providing a skid surface 101 which slidably rests on the upper surfaces 63 and 64 of the ways 31 and 32. The casting 100 is provided with flange portions 102 and 103 having holes 104 and 105 positioned for alignment respectively with the staggered rows of holes 95 and 96 in the ways 31 and 32, for the reception of the bolts 99 to secure the casting to the table 30, as described in connection with the previously described form.

Provided on each of the flange portions is a boss portion 106 having an arcuate slot 107 formed therein through which slots the lead screw 50 extends. Extending through each of the bosses is a pair of vertical holes 108 positioned on each side of the slot 107 through which bolts 109 extend, the bolts serving to clamp guide plates 110 to the central portion of the surface 101 of the casting, as shown best in Fig. 8. The guide plates are provided with outwardly facing notches 111 adapted to slidably engage the respective inner edges 39 and 40 of the ways 31 and 32, thus serving to restrain torsional and vertical movement of the casting relative to the table 30 and the Sampson post 21. Journaling means for the walking beam 22 is provided in this form of the invention by a pair of upwardly extending portions 112 which support bushings 113 journaling a shaft 114 on which the walking beam is supported by a bracket member 115 engaging the shaft 114 in a position between the portions 112, as shown. The casting 100 is provided with integral walls 116 forming a vertically disposed squared opening for the reception of the nut 81 for the purpose described in connection with the first form of the invention.

Although I have herein described two alternative forms of my invention it should be understood that I do not wish to be limited solely thereto, as I am fully aware of various features that might be changed and of other embodiments thereof that might be made. My invention should not be limited to the details of construction disclosed herein, but should be awarded the full scope of the following claims.

I claim as my invention:

1. A combination of the character described, including: a Sampson post; a laterally extending table on the upper end of said Sampson post; a bearing block slidably supported by said table, said block providing a journal for a walking beam; and means including a lead screw and a nut associated with said bearing block for sliding said bearing block and said walking beam from an operating position into a retracted position.

2. A combination of the character described, including: a Sampson post; a table on the upper end of said Sampson post; a lead screw rotatably supported on said table; a bearing block supported by said table and slidably thereon parallel to said screw, said bearing block providing a journal for a walking beam; and threaded means associated with said bearing block and operably engaging said screw to slide said bearing block on said table to move said

- walking beam from an operating position into a retracted position.
3. A combination of the character described, including: a Samson post; a table on the upper end of said Samson post; a lead screw rotatably supported on said table; a bearing block providing a journal for a walking beam and slideable on said table to move said walking beam from an operating position into a retracted position; guide means guiding said bearing block parallel to said screw; and threaded means associated with said bearing block and engaging said screw to move said bearing block on said table when said screw is rotated.
4. A combination of the character described, including: a Samson post; a laterally extending table on the upper end of said Samson post; a lead screw rotatably supported on said table; a bearing block providing a journal for a walking beam and slideable on said table to move said walking beam from an operating position into a retracted position; guide means guiding said bearing block parallel to said screw; threaded means associated with said bearing block and engaging said screw to move said bearing block on said table when said screw is rotated; means for rotating said screw; and means for restraining torsional and vertical movement of said bearing block relative to said Samson post.
5. A combination of the class described, comprising: a Samson post; a laterally extending table supported by said Samson post; a bearing block mounted for movement on said table; a walking beam secured to said bearing block; a screw rotatably supported adjacent said table; and a nut on said bearing block and in engagement with said screw, said nut being advanced upon rotation of said screw for moving said bearing block.
6. A combination of the class described, comprising: a Samson post; a laterally extending table supported by said Samson post; a bearing block mounted for movement on said table; a walking beam secured to said bearing block; a screw rotatably supported adjacent said table; and a nut removably positioned in a recess of said bearing block and in engagement with said screw, said nut being advanced upon rotation of said screw for moving said bearing block.
7. A combination of the class described, comprising: a Samson post; a laterally extending table supported by said Samson post; a bearing block mounted for movement on said table; a walking beam secured to said bearing block; a screw rotatably supported adjacent said table; a nut on said bearing block and in engagement with said screw, said nut being advanced upon rotation of said screw for moving said bearing block; and means cooperating between said table and said bearing block for holding said bearing block in proper position on said table.
8. A combination of the class described, comprising: a Samson post; a table supported by said Samson post, and having a pair of ways separated by a central space; a bearing block mounted for movement along said ways; a walking beam supported by said bearing block; a screw positioned in said central space, and being supported for rotational movement; and a nut in said space, said nut being in engagement with said bearing block and said screw, and being advanced along said screw when said screw is rotated.
9. A combination of the class described, comprising: a Samson post; a table supported by said Samson post, and having a pair of ways separated by a central space; a bearing block mounted for movement along said ways; means connected to said bearing block and extending into said central space for holding said bearing block in position on said table; a walking beam supported by said bearing block; a screw positioned in said central space, and being supported for rotational movement; and a nut in said space, said nut being in engagement with said bearing block and said screw, and being advanced along said screw when said screw is rotated.
10. A combination of the class described, comprising: a Samson post; a table supported by said Samson post, and having a pair of ways separated by a central space; a bearing block mounted for movement along said ways; means removably connected to said bearing block and extending into said central space for holding said bearing block in position on said table; a walking beam supported by said bearing block; a screw positioned in said central space, and being supported for rotational movement; and a nut in said space, said nut being in engagement with said bearing block and said screw, and being advanced along said screw when said screw is rotated.
11. A combination of the class described, comprising: a Samson post; a table supported by said Samson post, and having a pair of ways separated by a central space; a bearing block mounted for movement along said ways; means connected to said bearing block and extending into said central space, and forming channels into which the inner edges of said ways extend for holding said bearing block in position on said table; a walking beam supported by said bearing block; a screw positioned in said central space, and being supported for rotational movement; and a nut in said space, said nut being in engagement with said bearing block and said screw, and being advanced along said screw when said screw is rotated.
12. A combination of the class described, comprising: a Samson post; a laterally extending table supported by said Samson post, and having walls forming a central space; a bearing block mounted for movement on said table; a walking beam secured to said bearing block; a screw rotatably supported adjacent said table; a nut on said bearing block and in engagement with said screw, said nut being advanced upon rotation of said screw for moving said bearing block; and means connected to said bearing block and extending into said central space and cooperating with said walls of said table for holding said bearing block in proper position on said table.
13. A combination of the class described, comprising: a Samson post; a table supported by said Samson post, and having a pair of ways separated by a central space; a bearing block mounted for movement along said ways; a walking beam supported by said bearing block; a screw positioned in said central space, and being supported for rotational movement; a nut in said space, said nut being in engagement with said bearing block and said screw, and being advanced along said screw when said screw is rotated; and means connected to said bearing block and said table for fixing said bearing block to said table.

LESLIE A. RAWSON.
